UNITED STATES PATENT OFFICE.

JEREMIAH W. DIMICK, JR., AND JOSEPH JAGGER, OF RIFTON, NEW YORK.

STRETCHING APPARATUS.

SPECIFICATION forming part of Letters Patent No. 712,510, dated November 4, 1902.

Application filed March 24, 1902. Serial No. 99,614. (No model.)

To all whom it may concern:

Be it known that we, JEREMIAH W. DIMICK, Jr., and JOSEPH JAGGER, citizens of the United States, and residents of Rifton, in the county of Ulster and State of New York, have invented a new and useful Improvement in Stretching Apparatus, of which the following is a specification, taken in connection with the accompanying drawings, forming part of the same.

This invention relates to stretching apparatus, and relates more particularly to apparatus for stretching large rugs or other similar articles.

In the accompanying drawings, in which the same reference character refers to similar parts in the several figures, Figure 1 is a side elevation of this apparatus. Fig. 2 is a partial end view of the same. Fig. 3 is a perspective view showing the frame.

The table A, preferably formed with a flat top and with a series of legs A', serves to support the removable frame D. At one end of this table the movable slide B is mounted so as to move outward in a parallel manner from the adjacent edge of the table A. This slide is supported upon a series of guides A², which are rigidly secured to the table, and other guides B² in the form of round rods are rigidly secured to the slide and pass through suitable apertures in the table, so that the slide is accurately guided in its movements. A series of screws B³ are mounted in the slide, being held in position with respect thereto by the collars B⁴ and the worm-wheels B⁵, which are rigidly connected to the screws. The outer ends of these screws engage the threaded nuts B⁶, which are secured to the adjacent edge of the table A. The shaft C', which is operated by the wheel C, rigidly secured thereto, is mounted in a series of bearings C⁸, secured to the slide. This shaft has secured to it the worms C², which engage the worm-wheels B⁵, so as to rotate the screws B³ in unison. It will be evident, therefore, that by rotating the wheel C the screws B³ will simultaneously operate and will move the slide in a parallel manner with respect to the table A. The table has secured to its upper surface the retaining-ledge A³, and, if desired, a number of these ledges may be formed parallel to the edge of the table. The slide has rigidly secured there-

to a series of fingers B', which project up from the upper surface of the same.

The frame D, formed as is indicated in Fig. 55 3, consists of side pieces to which are rigidly secured the end pieces D'D² and the pressing-boards D³, spaced apart at suitable intervals. It is not necessary in all cases to mount the pressing-boards on the frame D, since they 60 may be mounted in any desired way, so long as they operate to support the seams of rugs or other articles while these rugs are stretched upon the frame. The strip E is movably mounted on the end piece D², being supported 65 by a series of guide-rods E³, rigid in the strip and entering suitable holes in the end piece D². The series of threaded rods E⁴ is also mounted to revolve in this strip, suitable collars being provided to engage the inner side of the strip 7c adjacent the end piece D², and the threaded ends of these rods engage threaded nuts secured to the end piece D². These threaded rods are actuated, if desired, by the removable handles E⁵, which engage the outer ends 75 of these rods, which are preferably squared. It will be seen that by this construction the strip is free to move at all times away from the end piece D², but that it cannot move toward the end piece any farther than the collars upon the threaded rods allow. The threaded rods therefore constitute the holding means to maintain the strip at a distance from the end piece of the extensible frame.

The end piece D' has pivoted to it the grip 85 D⁴, which moves about the hinges D⁵, the inner face of this grip being formed with a series of gripping pins or projections D⁶ to engage a rug or other material. This grip may be held down in operative position by a series 90 of clamps E⁶, which hold the grip in closed position. The strip E has the grip E' pivoted to it by the hinges E², this grip being formed and operating in a similar manner.

In using this apparatus for the stretching 95 of rugs the frame D is placed upon a table, the end piece D' of the frame being in engagement with the retaining-ledge on the table. The slide is operated so that the fingers B' engage the strip E in the manner indicated 100 in Fig. 1. A rug F is then secured to the frame by clamping its edges by means of the grips. The handle C is then operated to force the slide B outward, the fingers B' engaging

the strip E of the frame, and thereby stretching the rug in a parallel manner and to any desired extent. Since the seams F' are supported by the boards D⁸, they may be readily 5 pressed while the rug is stretched, and the rug may therefore be given a very smooth appearance. The handles E⁵ may be used to operate the threaded rods E⁴, so that the collars on these rods engage the strip E. Then if the 10 slide is moved back toward the table by the screws this holding means keeps the strip out and maintains the frame in extended position, so as to keep the rug stretched. The frame and rug may then be readily removed from 15 the table and may be placed in any desired position while the rug is drying. It will be seen that in this way the rugs are stretched to any desired extent, and after they are stretched they may be stored in this stretched condition 20 upon the light frames, which occupy but little room, while the table, with its heavy mechanism, may be used in connection with other frames. If desired, the table may be formed with a number of ledges A⁸ to engage frames 25 of different sizes, and in some instances it is not necessary to employ the stretching mechanism on the table, since the threaded rods may be operated to stretch a rug mounted on the frame.

30 It is of course understood that many modifications may be made in this invention without departing from the spirit of the same. Parts of this invention may furthermore be used without employing all of the same, and 35 parts of this invention may be used in connection with other devices by those skilled in this art. We do not, therefore, wish to be limited to the disclosure which we have made in this case; but what we claim as new and 40 what we desire to secure by Letters Patent is set forth in the appended claims.

We claim—

1. In stretching apparatus, a table provided with a ledge, a movable slide mounted at one 45 end of said table, screws having worm-wheels secured thereto mounted in said slide to engage said table, a shaft having a series of worms to engage said worm-wheels, fingers on said slide and a frame to coöperate with said 50 table, said frame comprising end pieces and pressing-boards and a strip movably mounted in one of said end pieces, threaded rods in said strip engaging said end piece, a pivoted grip mounted on said strip and provided with

pins to clamp material to said strip, a similar 55 pivoted grip secured to the opposite end piece, said frame coöperating with said ledge and said fingers on said table.

2. In stretching apparatus, a table provided with a ledge, a slide mounted in guides at one 60 end of said table, screws provided with worm-wheels mounted in said slide and engaging said table, a shaft mounted in bearings on said slide, worms on said shaft engaging said worm-wheels to simultaneously actuate said 65 screws to move said slide in parallel position with said table, an extensible frame comprising pressing-boards, grips to clamp material to the ends of said frame and holding means to maintain said frame in extended position. 70

3. In stretching apparatus, a table, a slide mounted at one end of said table, screws having worm-wheels secured thereto mounted in said slide to coöperate with said table, a shaft, worms secured to said shaft to engage said 75 worm-wheels to simultaneously operate said screws and an extensible frame to coöperate with said table comprising pressing-boards, grips and holding means to maintain said frame in extended position. 80

4. In stretching apparatus, a table, a slide mounted at one end of said table, means to move said slide with respect to said table, an extensible frame provided with grips engaging said slide and said table and pressing- 85 boards to support the seams of articles held on said frame.

5. In stretching apparatus, a frame having end pieces, pressing-boards secured to said frame between said end pieces, a movable 90 strip mounted in one of said end pieces, means to move said strip with respect to said end piece and a grip mounted in said strip.

6. In stretching apparatus, an extensible frame, holding means on said frame to secure 95 an article thereto, means for extending said frame, means to maintain said frame in extended position and pressing-boards to support the seams of said article.

7. In stretching apparatus, an extensible 100 frame to support an article, means to extend said frame and pressing-boards to support the seams of said article.

JEREMIAH W. DIMICK, JR.
JOSEPH JAGGER.
